DESIGN FOR A CHRISTMAS TREE ORNAMENT

Vincent P. O'Brien, Belle Harbor, N. Y.

Application October 21, 1947, Serial No. 142,059

Term of patent 14 years

(Cl. D29—1)

To all whom it may concern:

Be it known that Vincent P. O'Brien, a citizen of the United States, residing at Belle Harbor, New York, in the county of Queens and State of New York, has invented a new, original, and ornamental Design for a Christmas Tree Ornament, of which the following is a specification, reference being had to the accompanying drawing, forming a part thereof.

In the drawing:

Fig. 1 is a perspective view of a Christmas tree ornament, showing my new design;

Fig. 2 is a rear elevational view;

Fig. 3 is a side elevational view;

Fig. 4 is a top plan view; and

Fig. 5 is a bottom plan view of the same.

I claim:

The ornamental design for a Christmas tree ornament, as shown.

VINCENT P. O'BRIEN.
